PROCESS FOR REFINING UNWASHED RAW CANE SUGAR

Santino Paul Marino, Tarrytown, N.Y., assignor to Corn Products Company, New York, N.Y., a corporation of Delaware
No Drawing. Filed Feb. 3, 1964, Ser. No. 342,294
14 Claims. (Cl. 127—63)

The present invention relates to a process for refining raw cane sugar. More particularly, the present invention relates to a process, including electrodialysis, for refining raw cane sugar.

Commercial raw cane sugar refiners usually wash the raw sugar crystals by a first step called affination. This step consists of removing the adhering film of molasses from the surface of the raw sugar crystal. The separation is accomplished by co-mingling the raw sugar with a heavy sugar syrup (65°—70° Brix) and then purging the mixture in a centrifuge, followed by washing with water after the syrup has been spun off. This step dissolves the film of molasses but also a part of the sucrose, resulting in a removal of 9—14% of the initial raw sugar weight. The syrup spun off from the centrifuge and the washings makes up the affination syrup. It contains most of the molasses, some of the ash, sucrose, invert sugars, and organic non-sugar substances originally present in the raw sugar.

The affination syrup is put through various purification steps to recover as much of the sugar as possible. Generally, the affination syrup is treated with a defecation and filtration step to clarify the syrup. After clarification, the syrup is partially decolorized, followed by concentration to crystallize out the sugar. The remaining mother liquor is concentrated by vacuum evaporation of the water to crystallize out a second crop of crystals. The process of crystallization is repeated until as much sugar as possible has been recovered. The remaining syrup, after the last crystallization, is known as blackstrap molasses. The molasses solids constitute about 3—4% of the original raw sugar weight. The sugar crystallized from the affination syrup is usually low grade and is known as a soft or light brown sugar. When used as a liquid sugar, it may be known as amber syrup. Some refiners reprocess the crystallized sugar through the entire refining process to produce a high grade refined liquid sugar or crystalline sugar.

It is an object of the present invention to provide a process for refining sugar in which substantially 100% of the sucrose values are recovered as a refined substantially pure white crystalline sugar.

It is another object of this invention to provide a process for refining raw cane sugar in which no affination syrup or blackstrap molasses is obtained.

It is another object of this invention to provide a process for refining raw cane sugar wherein crystalline substantially pure white sucrose is obtained in large yields.

It is another object of this invention to provide a process for refining raw cane sugar in which a substantially pure colorless sucrose liquid sugar is obtained.

It is another object of this invention to provide a process for refining raw cane sugar and producing a high grade substantially pure refined liquid invert sugar.

Other objects of the present invention will be apparent from the following description.

The present invention is especially suitable for refining raw cane sugar, wherein the affination step is eliminated, by (1) forming a raw cane sugar aqueous solution having a Brix between about 30° and about 65°, (2) treating the raw cane sugar aqueous solution to substantially remove organic non-sugar substances or organic non-sugar substances and invert sugar, (3) decolorizing the sugar

2

solution, and (4) demineralizing the sugar solution by subjecting the solution to electrodialysis.

The present invention is also suitable for preparing liquid invert sugar from raw cane sugar, wherein the affination step is eliminated, by (1) forming a raw cane sugar aqueous solution having a Brix between about 30° and about 65°, (2) treating the raw cane sugar aqueous solution to substantially remove the organic non-sugar substances, (3) decolorizing the sugar solution, (4) demineralizing the sugar solution by subjecting the solution to electrodialysis, and (5) treating the sugar solution to invert the sucrose.

In a specific embodiment of the present invention, raw cane sugar is dissolved in water to form a solution having a Brix between about 30° and about 65°, preferably between about 45° and about 65°. The resulting solution is treated with lime in an amount between about 0.5 and about 3.5% by weight on a sugar solids basis (thus effecting the substantial removal of invert sugar). After 10 a holding period, the sugar solution is neutralized to a pH between about 6.0 and about 7.0 preferably between 15 6.5 and 6.8 with phosphoric acid. The neutralized solution is filtered. The sugar solution is next decolorized with a granular carbon to a color of less than 1.0 based 20 on the Horne scale, which will be described hereinafter. After decolorization, the ash of the decolorized sugar solution is reduced to less than 0.1% by electrodialysis. If desired, following the electrodialysis the demineralized 25 sugar solution is treated with cation and anion exchange resins to further reduce the ash content to less than 0.009% based on a sugar solids basis, and to reduce the color to less than 0.2 based on the Horne scale. The resulting sugar solution has a Brix in excess of 30°, a pH approximating 6.5, is water white in color, contains less 30 than 0.3% invert sugar, and contains less than 0.009% ash.

Raw cane sugar generally has a polarization of 96°—98°. The polarization represents the amount of sucrose in a specific weight of raw sugar. For example, 100 grams of raw sugar having a polarization of 96° will have 96 grams of sucrose. The remaining 4 grams will consist of water, ash, invert sugar, and organic non-sugars.

The raw cane sugars may vary from season to season, from one geographical source to another and from shipment to shipment. Thus the sucrose content may vary from 96—98%, the invert sugar content from 0.5—1.5%, the ash content from 0.3—1.0%, the organic non-sugar substances content from 0.5—2.0%, and the water content from 0.3—1.0%. As the polarization of the sucrose increases, the total impurity content (ash, non-sugars, water, and invert sugar) decreases. However, one or more of the individual impurities may not be decreased.

According to present commercial processes for refining raw cane sugar, it is estimated that 10% of the initial raw sugar weight is dissolved in the affination step. 100 grams of raw sugar with a polarization of 96° will result in the following approximate quantitative sugar product:

	Grams
60 Washed raw sugar	90
Low grade crystalline sugar or amber syrup (solids)	6.5
Blackstrap molasses on a solids basis	3.5

65 Heretofore it has not been economically possible to refine raw cane sugar without first producing an affination syrup. It is now possible by use of the combined steps of the present invention to refine raw cane sugar without producing an affination syrup. The process of the present invention omits the affination step, hence affination syrup and blackstrap molasses are not produced. As a result, the 9—14% of the raw sugar lost into low

grade sugar and blackstrap molasses by the usual refining process, can be refined into high grade refined sugars by the new process. The omission of the affination step results in a considerable reduction of the cost of the production of the high grade refined sugars. The process of the present invention is more direct, simpler, and consists of fewer process steps than the usual refining process.

There are basically three desirable commercial sugar products which may be obtained by the present process 10 as discussed below:

I. REFINED LIQUID SUCROSE

The process consists of the following steps:

- (1) Dissolution of the raw cane sugar.
- (2) Defaction (lime is used under certain conditions to remove most of the invert sugar followed by neutralization with phosphoric acid; the solution is clarified by one or more of the methods of filtration, centrifugation, settling or flotation).
- (3) Decolorization by the use of granular carbon.
- (4) Demineralization by electrodialysis.
- (5) Ion exchange (mixed cation and anion resins).
- (6) Concentration to the desired degree.

II. REFINED CRYSTALLINE SUCROSE

The steps one through four of the process for refining raw cane sugar, are also used in the refining process for making crystalline cane sugar. After step number 4 (demineralization by electrodialysis), the sugar syrup is evaporated (under vacuum) to a degree of supersaturation, and seeded to initiate crystallization of the sucrose. The crystallized sucrose is separated by centrifugation, washed, and dried in the usual crystalline refining method.

III. REFINED LIQUID INVERT SUGAR

Liquid invert sugar containing 48-56% invert sugar and 44-52% sucrose, on solids basis, or liquid invert sugar containing 95-99.9% invert sugar and 0.1-5% sucrose, on solids basis, is refined from raw cane sugar by the following process steps:

- (1) Dissolution of the raw cane sugar.
- (2) Defecation (using phosphoric acid and neutralizing with lime so as not to destroy the invert sugar. The solution is clarified by one or more of the methods of filtration, centrifugation, settling, or flotation).
- (3) Decolorization by the use of granular carbon.
- (4) Demineralization by electrodialysis.
- (5) Ion exchange. Cation resin only to reduce the pH and to remove cations.
- (6) Inversion of sucrose. The solution is held at elevated temperature until a desired amount of invert sugar has been obtained.
- (7) Ion exchange. Anionic exchange resin only to neutralize the sugar solution and to remove anions and color.
- (8) Concentration.

All color determinations are based on the Horne scale, wherein a dilute caramel solution is prepared of such concentration that when examined in a colorless glass water sample bottle, 3.34 cm. by 3.34 cm. by 11.43 cm., it matches the color of the standard glass when viewed against a similar bottle filled with distilled water. The standard glass has a reading of 10 and has been reproduced by a special amber glass. Standards are prepared from the caramel solution by dilution with distilled water to give readings from as high as 5.0 to as low as 0.1. The sample of liquid sugar is placed in the same sized bottle as the standards and comparison is made by transmitted light.

In order to have a fuller understanding of the present invention, the process steps outlined above will now be discussed in detail.

In the production of refined liquid sucrose from raw cane sugar commercial specifications require that the final product must contain less than 0.3% invert sugar,

less than 0.009% ash, less than 0.2 color based on the Horne scale, a pH between 6.5 and 7.2, and a concentration between 66.8° and 67.4° Brix.

When dissolving the raw cane sugar for step 1 of the refining process, the concentration of the solution may be between about 30° and about 65°, preferably between 45 and 65° Brix. The desired concentration may depend upon the method of clarification. For example, if filtration or centrifugation or both is to be used for clarification, the preferred raw cane sugar concentration is between 30 and 50° Brix. If settling or flotation is to be used for clarification, the preferred concentration is between 50 and 65° Brix.

For example, for the preparation of a 45° Brix raw cane sugar solution, 9.9 kg. of raw cane sugar are added to 11.4 liters of water while agitating. The solution is heated to between about 50° and 80° C. and agitated until all the sugar has dissolved. For other concentrations correspondingly increasing or decreasing amounts of raw sugar are used.

As previously mentioned, the invert sugar content of raw cane sugar varies from 0.5% to 1.5%. In order to meet specifications, it is necessary to reduce the invert sugar content to less than 0.3%. This is accomplished by the action of lime at increased temperature for a defined period of time. The concentration of lime, temperature, and the time required to reduce the invert sugar content are related. As the lime concentration is increased, with temperature remaining constant, the time for reducing the invert sugar content to less than 0.3% is decreased. As the temperature is increased, with the lime concentration remaining constant, the time for reducing the invert content is also decreased. However, high temperature may result in undesirable increase in color. It has been found that a temperature of about 85° C. resulted in optimal invert reduction at all levels of lime concentration without objectionable increase in color. Increasing the lime concentration and using a temperature of about 85° C. not only reduced the invert sugar content to less than 0.3% and decreased time requirement, but also effected an increase in color removal. Table I demonstrates the relationship between lime concentration, color, and time for the reduction of the invert sugar content to less than 0.3% at a temperature of about 85° C.

TABLE I

Percent Lime	Time, min.	Percent Invert	Color
0	0	1.23	42
0.6	90	0.44	54
1.0	60	0.19	39
2.0	15	0.17	26
3.0	10	0.08	16

55 The lime concentration is on sugar solids basis. The color is based on the Horne scale. After each time period for each level of lime concentration, the solution was neutralized with phosphoric acid to a pH between about 6.0 and 7.0, preferably between 6.5 and 6.8 and filtered to effect removal of organic non-sugar substances. The invert sugar and color values were determined on the filtrates. It is readily seen from the data above that with increasing lime concentration there is a progressive reduction of invert sugar content, a decrease in the time required for the reduction of the invert content, and an increasing amount of color removal.

60 The clarified cane sugar solution is decolorized to a color of less than 1.0 Horne scale by the use of granular carbon. The sugar solution should be maintained at a temperature less than 85° C. and it should remain in contact with the carbon for about 4 hours. Carbon may be used in amounts up to 10% of the sugar solids to be decolorized. The amount used will depend on the amount of color in the clarified sugar solution. Bone char or powdered vegetable carbon may also be used to de-

colorize the clarified sugar solution. Either of these carbons may be used in addition to granular carbon. Regardless of which carbon or combination of carbons is used, the color must be reduced to less than 1.0 Horne scale reading at this point in the process.

The ash of the decolorized sugar solution at a temperature between about 50° and 60° C. is reduced to less than 0.1% on a solid sugar basis by electrodialysis. The method involves the use of ion exchange membranes which are composed of a fabric backing impregnated with ion exchange resins. These may be 0.0635-0.127 cm. thick, and are of two types, cation and anion. The cation exchange membranes are permeable only to cations and the anion exchange membranes are permeable only to anions. These membranes are arranged in a stack made up of pairs of membranes of alternating permeability between two electrodes. The membranes are separated by spacers which serve as gaskets and direct the flow of liquid between the membranes.

In order to effect demineralization by electrodialysis, the sugar solution containing dissolved salts (ionized cations and anions) is passed through the chamber having a cation exchange membrane on one side and an anion exchange membrane on the other, while water as a dilute electrolyte (0.02 N NaCl) is passed through chambers on each side of the chamber containing the sugar solution. This system is repeated in multiples throughout the stack. An E.M.F. is applied through the electrodes and this driving force causes cations to move through the cation exchange membranes and anions to move through the anion exchange membranes. Since cations cannot pass through the anion exchange membrane, and anions cannot pass through the cation exchange membrane, the cations and anions having passed into the water stream cannot continue into the next chamber containing the sugar solution, but are trapped and removed by water as wastes.

Decolorized sugar solutions with sugar concentrations ranging from 30° to 65° Brix, and containing from 0.3 to 1.5% ash (sugar solids basis) have been successfully demineralized by electrodialysis to an ash content of less than 0.1%.

In the demineralization of decolorized sugar solutions by electrodialysis, there is a consistent polarization at the anion exchange membrane, resulting in a marked decrease of the pH of the sugar solutions resulting in undesirable inversion of sucrose. This polarization is a result of the fact that the sugar solution, immediately adjacent to the anion exchange membrane, is devoid of ions necessary to carry the current, consequently the water of the sugar solution undergoes electrolysis. The hydroxyl ion of the water passes through the anion exchange membrane leaving a residual hydrogen ion. Concentration of the hydrogen ions increases as indicated by the persistent drop in pH with time. This polarization, resulting in a decrease of the pH of the sugar solution, occurs even when a very low current density, far below the determined polarization current density, is used.

The difficulty of the drop of pH of the sugar solution and resulting inversion of the sucrose is overcome by controlling and maintaining the pH of the sugar solution between 6 and 7, preferably between 6.5 and 6.8 by the addition of small amounts of a solution of sodium hydroxide during the demineralization.

The electrodialyzed sugar solution at a temperature between about 48° and 52° C. from the preceding step is put through cation and anion exchange resins to reduce the ash content to less than 0.009% (sugar solids basis) and to reduce the color to less than 0.2 Horne scale. The cation and anion exchange resins are preferably a mixed ion exchange resin consisting of a homogeneous 1:1 mixture of a carboxylic acid-tape cation exchange resin and a quaternary amine-type anion exchange resin. The carboxylic acid-type cation exchange resin is used in order to prevent inversion of sucrose.

If for some reason, after the ion exchange treatment, the color is above 0.2, or if turbidity is present, the sugar solution may be treated with 0.2 to 0.3% powdered vegetable carbon and filtered.

5 The clear solution from the preceding step is concentrated under vacuum to the desirable sucrose concentration. In order to meet commercial standards, this concentration lies between 66.8° and 67.4° Brix.

10 In the process for the production of high grade refined crystalline sucrose, containing less than 0.05% invert sugar, less than 0.3 color and less than 0.015% ash, the first four steps of the preceding process are used. The clear sugar solution from the demineralization by electro-

15 dialysis step is evaporated under vacuum at a temperature between about 35° C. and about 85° C. until a supersaturated concentration is obtained (above 75° Brix). When this condition has been obtained, the sugar solution is seeded with very fine crystalline refined sucrose. Crystallization is allowed to take place and the

20 crystals allowed to grow to the proper size. The crystals of the mother liquor are then transferred to a basket centrifuge or other separation means from which the mother liquor is separated. The remaining crystals are washed one or more times with water. The mother liquor and the washings are evaporated to a supersaturated sugar concentration and recycled to the crystallization step. The evaporation, crystallization, crystal growth, crystal separation, and crystal washing with water are repeated until as much sucrose as possible is recovered

25 from the sucrose solution. The sucrose crystals are collected, mixed, and air dried.

The process for the production of the high grade refined liquid invert sugar containing between 48 and 56% invert sugar, on solids basis, and between 44 and 52% sucrose, on solids basis, differs slightly from the two processes set forth above, since it is not necessary to remove the invert sugar already present. The final refined liquid invert sugar will have an ash content less than 0.009%, a color reading less than 0.30 on a Horne scale basis, a pH between 5.0 and 5.6 and a sugar concentration between 76.0° and 76.6° Brix.

30 The raw cane sugar is dissolved with water to form a solution having a Brix between about 30° and about 65°, preferably between about 45° and 65°. At a temperature between 50° and 80° C. the resulting solution is then clarified by the addition of phosphoric acid to the raw cane sugar solution. The quantity of phosphoric acid should be sufficient to contain 0.1 to 0.15% P₂O₅ on the basis of sugar solids. After mixing at a temperature of about 85° C. for a few minutes, a suspension of lime is added to neutralize the raw cane sugar to a pH of 7.0 to 8.0, preferably between 7.2 and 7.6, the resulting suspension is filtered thereby clarifying the raw cane sugar solution and effecting the removal of organic non-sugar substances.

35 The resulting clarified solution is then decolorized with granular carbon in accordance with the preceding decolorization step discussed above.

40 The resulting decolorized solution is subjected to demineralization by electrodialysis. The electrodialysis process is essentially the same as that described in the preceding process. However, the polarization which occurs in both the liquid sucrose process and the crystalline sucrose process, also occurs in the electrodialysis demineralization of the sugar for the liquid invert sugar product. However, the decrease in pH of the sugar solution due to the polarization, results in some inversion of the sucrose which rather than being a disadvantage, in this case is an advantage since the final liquid invert sugar must contain about 50% invert sugar. Thus the maintenance of the pH between 6 and 7 with a solution of sodium hydroxide, as in the previous process, is not necessary in this process.

The resulting demineralized solution is put through a strong sulphonic acid-type cation resin. Practically all the cations are removed and the pH is reduced to about 3.0 and the temperature maintained at about 85° C. for approximately 30 minutes. After this period of time there is approximately 50% invert sugar. For the production of a refined liquid invert sugar containing between 95 and 99.9% invert sugar, on solids basis, and between 0.1% and 5% sucrose, on solids basis, the holding time required for the specified sugar solution described above is about one hour. However, it should be pointed out the holding time is not rigid. Variations in temperature, Brix, concentrations and pH of the cation resin treated solution will result in variation of the rate of sucrose inversion and thus the amount of invert sugar produced in a given time.

For the liquid invert sugar containing 48-56% invert sugar and 44-52% sucrose, the color should be reduced to less than 0.30 on a Horne scale basis. The ash should be less than 0.009% and the pH should be neutralized to a pH between 5 and 5.6, after the anion exchange treatment.

For the liquid invert sugar containing 95-99.9% invert sugar and 0.1-5% sucrose, the color should be less than 0.6 on a Horne scale basis. The ash should be less than 0.015% and the pH should be neutralized to between 5.0 and 5.6, after the anion exchange treatment.

Following the inversion step, the liquid invert sugar cooled to a temperature between about 48° and 52° C. is subjected to ion exchange treatment with an anion resin only, to neutralize the low pH inverted sugar solution and to remove the anions as well as to remove color.

The clear liquid invert sugar containing 48-56% invert is concentrated under vacuum to a Brix between 76.0 and 76.6°. The clear liquid invert sugar containing 95-99.9% invert is concentrated under vacuum to a Brix between 71.7° and 72.3°.

The following specific embodiments are included for purposes of exemplification only and in no way are intended to limit the scope of this invention.

Example I.—Production of refined liquid sucrose from raw cane sugar

A 45° Brix raw cane sugar solution is formed by adding 9.9 kilograms of raw cane sugar to 11.4 liters of water while agitating. The solution is heated to between about 50° and 80° C. and agitated until all the sugar has dis-

75% phosphoric acid, about 0.5% filter aid is added, and the solution is filtered.

The clarified solution is decolorized by the use of 0.71 kilogram of granular carbon to a color of 0.7 (Horne scale). The carbon is poured into 4 columns (5.08 cm. inside diameter, 38.1 cm. long) each containing about 0.18 kilogram of carbon. The columns are connected in series and kept in a hot water bath. The clarified sugar solution at a temperature of about 70° C. is put through the columns, with a downward flow, discharging from the fourth (last) column at a rate of 4 ml. per minute.

The clarified decolorized sugar solution at a temperature between 50° and 60° C. is passed through an electro-dialyzer cell consisting of a 9" x 10", 20 cell pair electric membrane electrodialysis stack to reduce the ash content to less than 0.1% (sugar solids basis). The pH of the sugar solution is maintained between 6 and 7, preferably between 6.5 and 6.8 by the addition of about 40 ml. of a 10% sodium hydroxide solution (for each 10 liters of sugar solution treated) in incremental amounts during demineralization. Using the above conditions, the ash content is reduced to 0.026% (sugar solids basis) in one hour.

The electrodialyzed demineralized sugar solution from the previous step is put through a mixed cation and anion exchange resin bed to reduce the ash content to less than 0.009% (sugar solids basis) and the color to less than 0.2 (Horne scale). A carboxylic type of cation exchange resin is used in order to prevent inversion.

The solution is brought to a temperature between about 48° and 52° C. and put through a column containing about 280 cc. of a homogeneous mixture of cation exchange resin and anion exchange resin in a ratio to each other of about 1:1.

The rate of flow through the column is maintained at 10 ml. per minute. The composite effluent sugar solution has an ash content of 0.001% (sugar solids basis), a pH of 6.5 and a color less than 0.2 (Horne scale). The solution is concentrated under vacuum to a sucrose concentration of about 67.4° Brix.

Example II

A raw cane sugar having a high ash content is processed according to the steps in Example I to yield a high grade, refined liquid sucrose. The table below sets forth analytical data obtained after completion of each step. The data are based on sugar solids, and the color is based on the Horne scale.

	° Brix	pH	Color	Percent Invert	Percent Ash
Step #1, dissolution (Raw Sugar)	46.5	6.3	41	0.57	0.925
Step #2, defecation with clarification; invert removal	43.9	7.2	43	0.09	0.921
Step #3, decolorization with granular carbon	43.3	6.3	0.7	0.14	0.922
Step #4, demineralization by electrodialysis	31.8	7.0	0.7	0.19	0.051
Step #5, demineralization by mixed cation and anion exchange resins	31.8	6.5	(1)	0.19	0.001
Step #6, concentration, under vacuum	67.4	6.5	(1)	0.19	0.001

¹ Water white.

solved. To this solution 99 grams of lime are added, and the solution heated to 85° C. and held at that temperature for about an hour. While confining to maintain the temperature at 85° C., the solution is neutralized to a pH between 6.0 and 7.0, preferably between 6.5 and 6.8 with

Example III

A raw cane sugar, having a high invert sugar content is processed according to Example I to yield a high grade, refined liquid sucrose. The table below sets forth analytical data obtained after completion of each step.

	° Brix	pH	Color	Percent Invert	Percent Ash
Step #1, dissolution (Raw Sugar)	45.6	6.1	42.3	1.32	0.41
Step #2, defecation with clarification; invert removal	43.4	6.7	68.1	0.25	0.66
Step #3, decolorization with granular carbon	40.9	6.9	1.0	0.26	0.64
Step #4, demineralization by electrodialysis	30.7	6.5	1.0	0.28	0.05
Step #5, demineralization by mixed cation and anion exchange resins	30.7	6.5	0.15	0.28	0.001
Step #6, concentration under vacuum	67.4	6.5	0.15	0.29	0.001

Example IV

A raw cane sugar is refined by the first four steps of Example I and then crystallized into a high grade, refined crystalline sucrose.

The clear sugar solution from step 4 of Example I is evaporated under vacuum at a temperature between about 35° C. and about 82° C. until a supersaturated sugar concentration is obtained (above 75° Brix). The concentrated solution is seeded with very fine crystalline refined sucrose and crystallization is allowed to take place. The crystals and mother liquor are transferred to a basket centrifuge from which the mother liquor is spun out. The remaining crystals are water washed. The mother liquor and water washings are either optionally concentrated and the crystallization process repeated, or recycled to an appropriate place in the process, for example, the liquor may be recycled to the crystallization step.

The sucrose crystals are air dried.

The table below sets forth analytical data obtained after completion of each step:

product. However, the decrease in pH of the sugar solution, due to the polarization resulting in some inversion of the sucrose, is not a disadvantage, but rather an advantage. Since the final liquid invert sugar should contain at least about 50% invert sugar, the maintenance of the pH between 6 and 7 with alkali as in the production of a refined liquid or crystalline sucrose is not necessary. At the end of the demineralization step, the pH is about 5.5.

The demineralized sugar solution is subjected to a strong sulfonic acid type cation exchange resin treatment. Substantially all of the cations are removed and the pH is reduced to about 3.0. The composite effluent sugar solution from the preceding step is adjusted to and maintained at a temperature of 85° C. for about 30 minutes. Analysis indicates there is 51% invert sugar (sugar solids basis). The holding time at 85° C. for 30 minutes is sufficient for the specific sugar solution described in the first 5 steps for the production of a refined liquid invert sugar containing 48-56% invert and between 44 and 52% sucrose.

	° Brix	pH	Color	Percent Invert	Percent Ash
Step #1, dissolution (Raw Sugar)	45.7	6.2	41.8	0.59	0.954
Step #2, defecation with clarification; invert removal	44.2	6.3	36.0	0.09	0.949
Step #3, decolorization with granular carbon	42.6	6.1	0.7	0.16	0.955
Step #4, demineralization by electrodialysis	32.2	7.0	0.5	0.21	0.026
Step #5, crystallization and drying-crystalline, dry sucrose	6.8	0.3		0.02	0.003

Example V

This example illustrates the preparation of liquid invert sugar. The process is generally the same as that for making refined liquid or crystalline sucrose, with the exceptions noted.

The concentration of the dissolved raw cane sugar may be between about 30° and 65°, preferably between 45 and 65° Brix. This step is the same as step 1 for making refined liquid or crystalline sucrose. In step 2 (defecation with clarification) the invert sugar is not removed. In the process for the production of liquid invert sugar, it is not necessary to remove the invert sugar from the raw cane sugar. Therefore, phosphoric acid is added first to the raw cane sugar solution. The quantity of phosphoric acid added should be sufficient to contain between 0.1 and 0.15% P₂O₅ on the basis of sugar solids. After mixing the acid with the raw cane sugar solution for a few minutes, a suspension of lime, about 25° Brix, is added to neutralize the raw cane sugar to a pH between 7.0 and 8.0, preferably between 7.2 and 7.6. A filter aid is added and the raw cane sugar heated to about 85° C. is clarified by filtration.

The decolorization with granular carbon (step 3) is the same as step 3 for making refined liquid or crystalline sucrose. The clarified sugar solution is then subjected to treatment by electrodialysis. The polarization which occurs as described in step 4 for making refined liquid or crystalline sucrose also occurs in the electrodialysis demineralization of the sugar for the liquid invert sugar

For the production of a refined liquid invert sugar containing between 95 and 99.9% invert sugar and between 0.1 and 5% sucrose, the holding time required for this specific sugar solution may be one hour. However, it is advantageous to make periodic analysis of the invert sugar so that a control on the percent invert may be maintained.

The holding time used is not rigid. Variations in temperature, Brix, concentration and pH of the cation exchange resin treated sugar solution will result in variation of the rate of sucrose inversion and thus the amount of invert sugar produced in a given time.

The liquid invert sugar solution from step 6 is adjusted to a temperature between about 48° and 52° C. and put through a column containing an anion exchange resin. The pH of the composite effluent sugar solution is 6.7. This pH is adjusted to 5.2 with dilute hydrochloric acid. After the pH adjustment if there is turbidity in the sugar solution or the color of the invert sugar liquid solution is more than 0.30 for the 48%-56% invert sugar and 45%-52% sucrose or more than 0.6 for the 95%-99.9% invert sugar and 0.1%-5% sucrose, the sugar solution should be treated with 0.2-0.3% powdered vegetable carbon and filtered.

The clear liquid invert sugar is concentrated under vacuum to a Brix between 76.0° and 76.6°.

The table below sets forth analytical data obtained after the completion of each step in the preparation of 51.6% liquid invert sugar:

	° Brix	pH	Color	Percent Invert	Percent Ash
Step #1, dissolution (Raw Sugar)	42.7	5.8	67.5	1.09	0.646
Step #2, defecation with clarification	36.1	7.4	32.7	1.21	0.541
Step #3, decolorization with granular carbon	30.9	7.2	0.9	3.45	0.556
Step #4, demineralization by electrodialysis	30.4	5.5	0.4	3.49	0.056
Step #5, cation removal and pH reduction					
Step #6, inversion of sucrose	30.4	6.7	0.13	51.0	0.003
Step #7, anion and color removal, neutralization					
Step #8, concentration (under vacuum)	76.2	5.2	0.13	51.6	0.007

The table below sets forth analytical data obtained after completion of each step in the preparation of 96.7% liquid invert sugar:

	° Brix	pH	Color	Percent Invert	Percent Ash
Step #1, dissolution (Raw Sugar)-----	45.5	6.0	67.7	0.9	0.336
Step #2, defecation with clarification-----	42.7	7.2	26.1	1.7	0.267
Step #3, decolorization with granular carbon-----	41.7	7.2	1.0	1.7	0.267
Step #4, demineralization with electrodialysis-----	31.1	6.0	0.8	4.4	0.028
Step #5, cation removal and pH reduction-----					
Step #6, inversion of sucrose-----	37.4	6.8	0.27	96.7	0.002
Step #7, anion and color removal neutralization-----					
Step #8, concentration (under vacuum)-----	71.8	5.5	0.30	96.7	0.002

Although the invention has been described by reference to certain specific embodiments thereof, it is to be understood that such matters are purely illustrative for the purpose of clarifying the invention and the invention is in no sense to be considered limited thereto. Numerous modifications and equivalents of the present invention will be apparent from the foregoing description to those skilled in the art.

I claim:

1. A process for refining unwashed raw cane sugar, wherein the affination step is eliminated, which comprises:

- (1) dissolving unwashed raw cane sugar in water to provide an aqueous solution having a Brix between about 30° and about 65°,
- (2) treating the raw cane sugar aqueous solution to substantially remove the organic non-sugar substances,
- (3) decolorizing the treated sugar solution, and
- (4) demineralizing the decolorized sugar solution by passing said solution through an electrodialyzer cell.

2. A process for refining unwashed raw cane sugar, wherein the affination step is eliminated, which comprises:

- (1) dissolving unwashed raw cane sugar in water to yield an aqueous solution having a Brix between about 30° and about 65°,
- (2) treating the raw cane sugar aqueous solution to substantially remove invert sugar and organic non-sugar substances,
- (3) decolorizing the treated sugar solution, and
- (4) demineralizing the decolorized sugar solution by passing said solution through an electrodialyzer cell.

3. A process for refining unwashed raw cane sugar, wherein the affination step is eliminated, which comprises:

- (1) dissolving unwashed raw cane sugar in water to yield an aqueous solution having a Brix between about 30° and about 65°,
- (2) removing invert sugar and organic non-sugar substances by treatment of the sugar solution with lime followed by neutralization with phosphoric acid,
- (3) decolorizing the treated sugar solution by treatment with granular carbon, and
- (4) demineralizing the decolorized sugar solution by passing the solution through an electrodialyzer cell to yield a refined sugar solution having a Brix above about 30°, a pH of about 6.5, and containing less than about 0.3% invert sugar and less than about 0.1% ash.

4. A process for preparing refined liquid sucrose from unwashed raw cane sugar which comprises:

- (1) dissolving unwashed raw cane sugar in water to form a solution having a Brix between about 45° and about 65°,
- (2) treating the resulting sugar solution with between about 0.5 and about 3.5% by weight of lime,
- (3) neutralizing the sugar solution with phosphoric acid to a pH between about 6.0 and about 7.0,
- (4) filtering the neutralized sugar solution,

15

- (5) decolorizing the treated sugar solution with granular carbon, and
- (6) passing the decolorized sugar solution through an

electrodialyzer cell to yield a sugar solution having a Brix above about 30°, a color index of less than 1.0 based on the Horne scale, a pH of about 6.5, and containing less than about 0.3% invert sugar and less than about 0.1% ash.

20 5. A process as in claim 4 wherein the refined sugar solution is subjected to further treatment with a mixed ion exchange resin to reduce the ash content to less than about 0.009% and the color index to less than about 0.2 based on the Horne scale.

6. A process as in claim 4 wherein the refined sugar solution is concentrated to a Brix of between about 66.8° and about 67.4°,

30 7. A process as in claim 4 wherein during electrodialysis the pH of the sugar solution is maintained between about 6.0 and about 7.0 by the addition of incremental amounts of sodium hydroxide.

8. A process as in claim 4 wherein the sugar solution is subjected to further treatment by evaporation and concentration to crystallize the sugar which is recovered as a substantially pure, white, dry crystalline sugar having an ash content of 0.004%, a color of 0.3 on a Horne scale basis, an invert sugar content of 0.02%, and a pH of 6.8.

35 9. A process for preparing liquid invert sugar from unwashed raw cane sugar, wherein the affination step is eliminated, by

- (1) dissolving unwashed raw cane sugar in water to form an aqueous solution having a Brix between about 30° and about 65°,
- (2) treating the raw cane sugar aqueous solution to substantially remove the organic non-sugar substances,
- (3) decolorizing the treated sugar solution,
- (4) demineralizing the decolorized sugar solution by passing the solution through an electrodialyzer cell, and
- (5) treating the sugar solution to invert the sucrose.

40 10. A process for preparing liquid invert sugar which comprises:

- (1) dissolving raw cane sugar in water to form a solution having a Brix between about 45° and about 60°,
- (2) treating the sugar solution with phosphoric acid in an amount sufficient to contain between about 0.10 and about 0.15% P_2O_5 on the basis of sugar solids,
- (3) neutralizing the sugar solution with lime to a pH between about 7.0 and about 8.0,
- (4) filtering the neutralized sugar solution,
- (5) decolorizing the sugar solution with granular carbon,
- (6) passing the decolorized sugar solution through an electrodialyzer cell,
- (7) subjecting the electrodialysis-treated sugar solution to treatment with a strong sulfonic acid-type cation exchange resin whereby the pH is reduced to about 3.0,
- (8) maintaining the temperature of the sugar solution at about 85° C. for a period of time sufficient to yield the desired amount of inversion, and

75

(9) adjusting the pH of the resultant liquid invert sugar to between about 5.0 and about 7.0.

11. A process for preparing liquid invert sugar from raw cane sugar wherein the affination step is eliminated, which comprises:

- (1) forming a raw cane sugar aqueous solution by dissolving raw cane sugar in water at a temperature between about 50° C. and about 80° C. to form a solution having a Brix between about 45° and about 65°,
- (2) treating the sugar solution with phosphoric acid in an amount sufficient to contain between about 0.1% and about 0.15% P₂O₅, on the basis of sugar solids,
- (3) neutralizing the sugar solution with lime to a pH between about 7.0 and 8.0,
- (4) heating the solution to about 85° C.,
- (5) clarifying the solution by filtration,
- (6) decolorizing the sugar solution by treatment with up to 10% granular carbon by weight to the weight of sugar solids at a temperature less than 85° C. with a contact time of 4 hours to a color on a Horne scale basis of less than 1.0,
- (7) demineralizing to an ash content of less than 0.1% by passing the solution through an electro-dialyzer cell at a temperature between about 50° and about 60° C.,
- (8) subjecting the electrodialysis-treated solution to treatment with a strong sulfonic acid-type cation exchange resin to reduce the pH to about 3.0,

5
10
20
25
30

(9) maintaining the resin treated solution at about 85° C. for a period of time sufficient to yield 48% to 56% invert sugar, and

(10) treating the inverted sugar with an anion exchange resin to neutralize the sugar solution to a pH between about 5.0 and about 7.0.

12. A process as in claim 11 wherein the resin treated solution is maintained at about 85° C. for a period of time sufficient to yield between 95 and 99.9% invert sugar.

13. A process as in claim 11 wherein the refined liquid invert sugar solution is concentrated to a Brix of between about 76.0 and about 76.6°.

14. A process as in claim 12 wherein the refined liquid invert sugar solution is concentrated to a Brix of between about 71.7° and about 72.3°.
